US00D455488S

(12) **United States Design Patent** (10) Patent No.: **US D455,488 S**
James (45) Date of Patent: ** Apr. 9, 2002

(54) **FEMALE INCONTINENCE CONTROL DEVICE**

(75) Inventor: **Larry W. James**, Lee's Summit, MO (US)

(73) Assignee: **Medical Technology & Innovations, Inc.**, Riviera Beach, FL (US)

(**) Term: **14 Years**

(21) Appl. No.: **29/134,979**

(22) Filed: **Jan. 3, 2001**

(51) LOC (7) Cl. **28-01**

(52) U.S. Cl. **D24/105**; D24/214

(58) Field of Search D24/105, 200, D24/211, 214; 600/29, 30

(57) **CLAIM**

The ornamental design for a female incontinence control device, as shown and described.

DESCRIPTION

FIG. 1 is a perspective view of a female incontinence control device, showing my new design;

FIG. 2 is a side elevational view thereof, the undisclosed opposite side being a mirror image.

FIG. 3 is a top plan view thereof.

FIG. 4 is a bottom plan view thereof.

FIG. 5 is an end view thereof; and,

FIG. 6 is an end view opposite the view shown in FIG. 5.
